UNITED STATES PATENT OFFICE.

ELMER E. HAUER, OF SPRINGFIELD, OHIO, ASSIGNOR, BY MESNE ASSIGNMENTS, TO ELLIOTT COMPANY, OF PITTSBURGH, PENNSYLVANIA, A CORPORATION OF PENNSYLVANIA.

TURBINE.

1,198,219.

Specification of Letters Patent. Patented Sept. 12, 1916.

Application filed February 18, 1916. Serial No. 79,092.

To all whom it may concern:

Be it known that I, ELMER E. HAUER, a citizen of the United States, residing at Springfield, in the county of Clark and 5 State of Ohio, have invented certain new and useful Improvements in Turbines, of which the following is a specification, reference being had therein to the accompanying drawings.

10 My invention relates to turbines and more particularly to a turbine adapted to travel through a tube with a cleaner, although it may be used for other purposes.

The object of my invention is to provide a 15 simple, strong, durable and efficient turbine that will stand the severe shocks and jars incident to its use and can be readily assembled and easily taken apart for examination and repairs.

20 It has been a common practice to construct the casing of turbines for tube cleaning by taking a bar of wrought steel and boring or hogging it out leaving an integral head or support for the front bearing. This is an 25 expensive process in which there is a great waste of material. To overcome this I have devised a construction in which I form the casing from an ordinary section of tubing, preferably the well known seamless Shelby 30 tubing. This is very much less expensive than hogging it out from a solid piece.

A further object is to provide a removable front head and bearing so constructed and arranged that they will not jar loose 35 and having means to hold the discharge openings through the respective parts in alinement.

With these and other objects in view my 40 invention consists of the constructions and combinations hereinafter mentioned and set forth in the claims.

In the drawings which form a part of this specification Figure 1 is a longitudinal section of a turbine embodying my invention, taken on the line 1—1 of Fig. 3. Fig. 45 2 is a longitudinal section taken on the line 2—2 of Fig. 3, and Figs. 3 and 4 are cross-sections on the lines 3—3 and 4—4 of Fig. 1 respectively.

50 Like numerals represent the same parts in the several views.

In the drawings 1 represents a tubular casing of uniform bore throughout its length and open at its respective ends. It

may be formed from a section of ordinary 55 tubing but I preferably employ for the purpose the well known Shelby seamless tubing. Within the tubular casing and intermediate of its ends an annular recess is cut into which a ring or short section of 60 tubing is expanded forming a stop 2 as shown in Figs. 1 and 2. A rear bearing member 3 is seated against the front side of said stop and is preferably provided with a bushing 4. A front bearing member 5 preferably provided with a bushing 6 is seated against the front end of a cylinder 7, the other end of said cylinder being seated against the rear bearing member forming a 65 spacer between said bearing members. 70

A turbine wheel 8 having buckets 9 and a central hub 10 and wearing plate 11 is screw-threaded to a shaft 12 against a shoulder 13 within the cylinder 7. Said shaft is journaled in the front and rear bearings, extends beyond the front end of the casing and is screw-threaded at 14 for the attachment of the tool to be driven. 75

A thrust bearing is provided between the turbine wheel and front bearing member 80 and may be of any suitable form but I preferably employ an anti-friction bearing having two disks 15 each having oppositely disposed hemispherical recesses opening through the outer walls so that when the 85 disks are riveted together by rivets 16 with balls 17 in said recesses, the balls will project slightly beyond the outside walls of said disks and contact with the wear plate 11 of the wheel and a like wear plate 18 90 seated in the front bearing member. The disks 15 form a holding member for the balls that permanently keep the balls in assembled position so that when the turbine is taken apart they will not drop out and 95 be lost. A plug 19 in the rear bearing member is removable so that the bushing in said bearing may be easily driven out.

A supply head 20 having the end of a supply conduit 21 secured therein by screws 100 22 is screw-threaded within the casing 1 and tightened against the stop 2 to securely hold the same in place. The stop 2 acts as a spacer between the supply head 20 and rear bearing member 3 forming a chamber having inclined inlet openings 23 through said member to direct the motive fluid to the buckets 9 of the wheel. 105

A discharge head 24 having a central tapered opening 25 is screw-threaded into the opposite end of the casing, said tapered opening contacting a corresponding taper of the front bearing member 5 and acting as a wedge to securely tighten and hold said member, as well as the cylinder 7 and rear bearing member 3 in the casing against said stop. Discharge openings 26 through the front bearing member 5 and through the discharge head 24 are provided and held in alinement by dowel-pins 27 seated in oppositely disposed openings in the respective parts. The combined length of the oppositely disposed openings is greater than the length of the pin and the diameter of the opening in the bearing member is slightly greater than the diameter of the pin so that in screwing the head into the casing against the bearing member there is sufficient play to insure the wedging or tightening of the parts in the casing against the stop.

Having thus described my invention I claim—

25. 1. In a turbine, a tubular casing open at its respective ends, an inwardly projecting stop secured to said casing intermediate of its ends, front and rear bearing members and a cylinder between said members, said cylinder and members being introduced through one end of said casing with means to hold the same against said stop, a supply head secured to the other end of said casing and a turbine wheel in said cylinder 30 having a shaft journaled in said bearing members, said supply head and rear bearing member being spaced apart by said stop and forming a chamber having inclined inlets through said bearing member to direct the motive fluid to the buckets of said wheel, substantially as described.

2. In a turbine, a tubular casing open at its respective ends, an inwardly projecting stop secured to said casing intermediate of its ends, front and rear bearing members and a cylinder between said members, said cylinder and bearing members being introduced through one end of said casing with means to hold same against said stop, a supply head secured to the other end of said casing, a turbine wheel in said cylinder having a shaft journaled in said bearings and a thrust bearing between said wheel and front bearing member, said supply head 45 and rear bearing member being spaced apart by said stop and forming a chamber having inclined inlets through said rear bearing member to direct the motive fluid to the buckets of said wheel, substantially as described.

3. In a turbine, a tubular casing open at its respective ends, an inwardly projecting stop secured to said casing intermediate of its ends, front and rear bearing members 50 having removable bushings therein and a

cylinder between said members, said cylinder and bearing members being introduced through one end of said casing with means to hold the same against said stop, a supply head secured to the other end of said casing, a turbine wheel in said cylinder having a shaft journaled in said bushings and a ball thrust bearing between said wheel and front bearing member, said supply head and rear bearing member being spaced apart by said stop and forming a chamber having inclined inlets through said rear bearing member to direct the motive fluid to the buckets of said wheel, substantially as described.

4. In a turbine, a casing having an open end, a journal bearing member introduced through said open end, a head screw-threaded to said casing against said member to tighten and hold it in place, said head and bearing member each having discharge openings and means engaging said parts to hold said discharge openings in alinement, substantially as described.

5. In a turbine, a casing having an open end, a journal bearing member introduced through said open end, means to limit the inward movement of said member, said member being tapered toward its outer end, a head screw-threaded to said casing and having a taper opening to engage the taper of said member to tighten and hold the same in place, said head and bearing member each having discharge openings and a dowel-pin arranged to engage said parts to hold said discharge openings in alinement, substantially as described.

6. In a turbine, a casing having an open front end, a cylinder in said casing, means to limit its rearward movement, a journal bearing member introduced through said open end and seated against said cylinder, said journal bearing member being tapered toward its outer end, a head screw-threaded to said casing and having a tapered opening to engage the taper of said member to tighten and hold the same in place against said cylinder, said head and bearing member each having discharge openings and a dowel-pin arranged to engage said parts to hold said discharge openings in alinement, substantially as described.

7. In a turbine, a tubular casing open at its respective ends, an inwardly projecting stop secured to said casing intermediate of its ends, front and rear bearing members and a cylinder between said members, a head screw-threaded to one end of said casing and having a central tapered opening to engage a taper of said front bearing member to wedge same within the casing and tighten and hold said cylinder and bearing members against said stop, a supply head secured to the other end of said casing, a turbine wheel in said cylinder having a

shaft journaled in said bearing members, said supply head and rear bearing member being spaced apart by said stop and forming a chamber having inclined inlets 5 through said rear bearing member to direct the motive fluid to the buckets of said wheel, substantially as described.

In testimony whereof I have hereunto affixed my signature in the presence of two witnesses.

ELMER E. HAUER.
